UNITED STATES PATENT OFFICE

153,304

DESIGN FOR A MATCHBOX

Lillie L. Myers, Coleman, Tex.

Application May 11, 1948, Serial No. 146,296

Term of patent 7 years

(Cl. D48—28)

To all whom it may concern:

Be it known that I, Lillie L. Myers, a citizen of the United States, residing at Coleman, in the county of Coleman and State of Texas, have invented a new, original, and ornamental Design for a Match Box, of which the following is a specification, reference being had to the accompanying drawing, forming part thereof.

I claim:

The ornamental design for a match box, as shown.

LILLIE L. MYERS.
